CLAIM

The ornamental design for a pillow with multiple replacable inserts, as shown and described.

DESCRIPTION

FIG. 1 is a front perspective view of the pillow,
FIG. 2 is a rear perspective view of the pillow of FIG. 1;
FIG. 3 is a front view of the pillow of FIG. 1;
FIG. 4 is a rear view of the pillow of FIG. 1;
FIG. 5 is a left side view of the pillow of FIG. 1, the right
side being a mirror image thereof
FIG. 6 is a rear view of the pillow of FIG. 1, with unfastened
back to allow for adding thereto or removing therefrom one
or more inserts;
FIG. 7 is a front view of the first insert configuration for
pillow of FIG. 1;
FIG. 8 is a front view of the second insert configuration for
pillow of FIG. 1; and,
FIG. 9 is a front view of the third insert = configuration for
pillow of FIG. 1.
The broken lines in the drawings represent portions of the
article or environmental subject matter, none of which form
part of the claimed design.
